(57) **CLAIM**

The ornamental design for an over-the-door towel bar, as shown and described.

DESCRIPTION

FIG. 1 is a perspective view of an over-the-door towel bar, showing our new design;

FIG. 2 is a front elevational view thereof;

FIG. 3 is a side elevational view thereof;

FIG. 4 is a rear elevational view thereof; and,

FIG. 5 is a perspective view of a second embodiment of an over-the-door towel bar, wherein the jagged broken lines form no part of the claimed design and the subject matter between the jagged lines is broken away to disclose indeterminate height.

The dotted-line disclosure of elements in the views is for illustrative purposes only and forms no part of the claimed design.
